(57) **CLAIM**

I claim, the ornamental design for a color coded stamped fastener, as shown and described.

DESCRIPTION

The patent or application file contains at least one drawing executed in color. Copies of this patent or patent application publication with color drawing(s) will be provided by the Office upon request and payment of the necessary fee.

FIG. 1 is a side elevation view of a first embodiment of a green color coded, stamped fastener showing my new design.

FIG. 2 is a top plan view of FIG. 1 thereof, with an indicia letter 'I' being imprinted or stamped on the head of the fastener.

FIG. 3 is a perspective view of FIG. 1 thereof.

FIG. 4 is another side elevation view of FIG. 1 thereof.

FIG. 5 is a top plan view of a second embodiment, having indicia for a slanted letter "I" imprinted or stamped on the head of the fastener; and,

FIG. 6 is a perspective view of FIG. 5 thereof.

The shadows and reflections displayed in the drawings form no part of the claimed design.
